HYDRAULICALLY SET WELL PACKER

Reuben C. Baker, Coalinga, Calif., assignor to
 Baker Oil Tools, Inc., Vernon, Calif., a corpora-
 tion of California

Application October 26, 1946, Serial No. 706,001

3 Claims. (Cl. 166—12)

1

The present invention relates to well packers adapted to be anchored in packed-off condition in casings, liners, and similar conduits positioned in well bores.

Certain types of well packers embody slips which are held initially in retracted position and which are expanded outwardly into anchoring engagement with the wall of a well casing by hydraulically operated instrumentalities. The slips may be held firmly in retracted position by one or more shear screws that are designed to rupture at a predetermined pressure of the fluid acting on the hydraulic setting mechanism of the particular tool employed. Difficulties are sometimes encountered, however, in achieving the tripping and setting of the slips at the predetermined pressure. Such difficulties are thought to be due to conditions in the well, including the relatively heavy viscosity of the mud and similar fluids within the well casing, and sand or other detritus that may tend to pack and foul the setting mechanism. As a result, it oftentimes occurs that the slips can only be set at an inordinately high pressure or the setting cannot be achieved at all upon elevation of the pressure of the fluid in the tool to a considerable extent above the predetermined value.

Accordingly, it is an object of the present invention to provide a well packer in which assurance is had that the slips will be tripped and released for movement from their retracted position to anchored position against the casing by hydraulic instrumentalities at approximately the predetermined value at which such release is to occur.

One form which the invention may assume is exemplified in the following description and illustrated by way of example in the accompanying drawings, in which:

Fig. 1 is a longitudinal section through a well packer embodying the invention, positioned in a well casing with certain of its parts in retracted position.

Fig. 2 is a quarter longitudinal sectional view similar to Fig. 1, disclosing the well packer partially set in the casing.

Fig. 3 is a quarter longitudinal sectional view similar to Fig. 1, illustrating the packer fully anchored in packed-off condition within the well casing.

Fig. 4 is a cross-section taken along the line 4—4 on Fig. 1.

As disclosed in the drawings, a well packer A is detachably secured to a setting tool 10 forming the lower end of a tubular string B running to the top of the well bore and by means of which

2

the packer is lowered to the desired setting or anchoring point within the well casing C.

The packer A includes a tubular body 11 having an abutment and guide 12 threaded on its lower end and a head 13 at its upper end around which the skirt 14 of a cylinder is mounted. A cylinder head 15 extends inwardly from the lower end of the skirt and carries suitable side seal rings 16 in ring grooves 17 slidably engaging the external surface of the body 11. Suitable side seal rings 18 are also disclosed in body head grooves 19 for slidably engagement with the interior of the skirt 14.

A set of upper segmented slips 20 are disposed around the body immediately below the cylinder head 15. These slips are held initially in retracted position by shear screws 21, attaching them to an upper conical expander 22 initially secured to the body 11 by one or more shear screws 23. The converging surfaces of the upper set of slips 20 and upper expander 22 are so disposed with respect to one another as to secure the packer against movement in an upward direction within the casing C, or similar well conduit, following outward expansion of the slips 20 into engagement with the casing.

A set of lower segmental slips 24 is provided adjacent the abutment 12, and these slips are also secured by shear screws 25 to a lower tapered expander 26 attached initially to the body 11 by one or more shear screws 27. The direction of taper on the exterior of the lower expander 26 and the taper on the cooperable surfaces of the lower slips 24 are such as to hold the well packer against movement in a downward direction following expansion of the slips 24 outwardly to casing engaging position.

A suitable lock is provided between the body 11 and lower expander 26 to permit upward movement of the body within this expander, but to preclude its downward movement. Such lock may be constituted by a split tapered wedge ring 28 received within the tapered groove 29 in the lower expander 26.

A suitable packing, such as a packing sleeve 30 of rubber or similar pliant material, is disposed around the body between the upper and lower expanders 21, 26. The ends of the packing sleeve 30 are received within annular pockets 31 formed between the expander skirts 32 and the exterior of the body 11.

The setting tool 10 is threaded, as by a left-hand thread 33, into the head 13 of the packer body. This setting tool has a lower head 34 carrying suitable side seals 35 for sealing engagement

with the inner wall of the body. The head 34 is disposed below body ports 36 positioned between the body and cylinder head seals 18, 16 to establish communication between the interior of the body 11 and the elongated annular clearance space 37 between the body head 13 and cylinder head 15. Elongated ports 38 in the form of slots extend through the setting tool 10 between its threaded portion 33 and head 34, establishing communication between the interior of the setting tool 10 and elongated annular space 39 between the exterior of the setting tool 10 and the interior of the body 11.

The well packer A is run in the well bore with its parts in retracted position, as disclosed in Fig. 1. The cylinder 14, 15 is held initially in its upper position by one or more shear screws 40, securing the skirt 14 to the body head 13. During the lowering of the packer in the well casing, the tubular string B is automatically filled with the fluid in the well casing, which flows upwardly through the central passage 41 in the setting tool head 34 into the interior of the setting tool and tubular string B.

Upon reaching the point in the well casing at which the packer is to be anchored in packed-off condition, a trip ball 42 is dropped into the tubing string B and is allowed to gravitate or is pumped downwardly into engagement with a seat 43 in the setting tool head, closing the passage 41 through the head and enabling the pressure of the fluid in the tubular string B, setting tool 10, slotted ports 38, elongate annular space 39, body ports 36 and elongate cylinder space 37 to be increased to a predetermined degree sufficient to overcome the shear values of the screws 40, 21 holding the cylinder 14, 15 in its uppermost position and the upper slips 20 to the upper expander 22. Following rupture of these screws, the cylinder is moved downwardly to slide the upper slips 20 down along the tapered surface of the upper expander 22 and outwardly into engagement with the casing (Fig. 2).

The shear screws 23 securing the upper expander to the body 11 have a greater shear value than the cylinder screws 51 and the screws 21 holding the upper slips 20 to the upper expander 22. The screws 27, 25 holding the lower expander 26 to the body 11 and the lower slips 24 to the lower expander have a greater shear value than the screws 23 extending through the upper expander 22. It is, accordingly, apparent that only the first two sets of screws mentioned above are first sheared, moving the upper slips 20 to anchored position against the casing. Following such anchoring, the tubular string B is pulled upwardly to first disrupt the screws 23 holding the upper expander 22 to the body 11, and then move the packer body 11 upwardly within this upper expander, carrying the lower expander 26 with the body toward the upper expander 22 (which is held against upward movement by the slips 20), foreshortening the packing sleeve 30 and expanding it outwardly into firm sealing engagement with the casing, and also firmly into engagement with the exterior of the packer body 11. As soon as the packing structure has been thus packed off between the body 11 and casing C, a continuation of the upward strain on the tubular string B shears the lower expander screws 27 and lower slip screws 25, causing the abutment 12 to move the lower slips 24 upwardly along the lower expander 26 and outwardly into firm anchoring engagement against the casing (Fig. 3).

Following the complete setting of the upper and lower slips 20, 26, in the manner described, the tubular string B may be rotated to the right to unscrew the setting tool 10 from the body head 13 at the left-hand thread 33, allowing the tubular string B and setting tool 10 to be removed from the well casing C.

The upper slips 20 prevent upward movement of the well packer and its body 11 with respect to the well casing. The lower slips 24 prevent downward movement of the well packer and its body with respect to the well casing, the downward moving tendency of the body being transmitted through the wedge lock 28, 29 to the lower expander 26, and through the slips 24 to the casing C. Thus, the well packer is prevented from moving in either longitudinal direction.

Although the screws 21 securing the upper slips 20 in retracted position have a predetermined shear value and are designed to rupture upon the imposition of a predetermined pressure to the fluid within the elongate cylinder space 37, actual experience has demonstrated that sometimes much higher pressures than the predetermined amounts are required to shear the screws, or the screws cannot be sheared at all regardless of the extent of pressure placed on the fluid in the setting tool 10 and packer body 11. It is believed that such inability to set the slips at the desired pressure is due to the plugging of parts of the tool by heavy drilling muds, sand or other detritus that might be present in the well packer, acting as a solid barrier against the transmission of fluid to the lower cylinder head 15, in order to urge it downwardly with sufficient force against the upper set of slips 20. The fluids and combinations of fluids and solid particles in the well tool may also prevent the pressure imposed on the fluid in the tubing string B and setting tool 10 from being transmitted through the various ports 36, 38 against the full area of the cylinder head 15.

The present invention overcomes the above noted disadvantage of setting the tool at much higher pressures than intended. It is to be noted that the setting tool itself is provided with relatively long slotted ports 38, which permits passage of fluid and fluid-like materials, but prevents the passage of large particles as might tend to plug the ports 36 of the tool and the cylinder space 37. It is also to be noted that a relatively long annular space 39 is provided between the ported portion 38 of the setting tool and the inner wall of the packer body 11 and that the body ports 36 are located intermediate the ends of the slotted ports 38 in the setting tool and the annular space 39. Because of this arrangement, any materials that may plug or restrict the slotted ports can do so only along part of its length, and any materials that may settle in the annular space 39 between the setting tool and body can close only part of such space. However, the body ports 36, themselves, will still be in full communication with the annular space 39 around the setting tool for the purpose of receiving fluid under pressure from within the setting tool, which pressure is transmitted freely through a sufficiently open area of the slotted ports 38 and across a sufficiently open area in the annular space 39 into and through the cylinder ports 36.

70 To further preclude the effects of plugging of the hydraulic portion of the mechanism, which may prevent transmission of the entire fluid pressure over the full area of the cylinder head 15, the cylinder head is spaced a substantial distance below the body ports 36, the latter exiting

into the elongate annular cylinder space 37 formed transversely between the inner wall of the cylinder skirt 14 and an intermediate portion 45 of the body 11, which is greater in diameter than the internal diameter of the cylinder head 15 but substantially less in diameter than the internal diameter of the cylinder skirt. The intermediate body head portion 45, in effect, forms a shoulder against which the cylinder head 15 may abut to provide the relatively long annular cylinder space 39 between the cylinder head 15 and body head 13 when the cylinder 14, 15 is in its uppermost position. The body ports 36, themselves, communicate with the elongated cylinder space 37 at its upper end.

The fluid under pressure is transmitted through the body ports 36 and into the cylinder space 37. In view of the relatively large length of this space 37, when the upper slips 20 are in retracted position, any materials of a solid or non-fluid transmitting nature that might be present in the space 37 can have very little, if any, effect upon the transmission of the pressure against the full annular area of the cylinder head 15, since the ports 36 are sufficient in number and the solid particles that might be present in the cylinder space 37 will be insufficient to fill this space along its entire length. Part of the elongate space 37 might be plugged, and the fluid pressure can still be transmitted around the plugged portion for action against the head 15. An effective annular area around the cylinder space will still be present to enable the pressure to be transmitted either through or around the solid particles, and possibly to press the particles themselves firmly against the cylinder head 15. It is believed that the provision of substantially no initial clearance space between the cylinder head and the body head as in prior devices, permits the relatively short annular cylinder space to be plugged very readily by non-fluid materials, and presents transmission of the fluid pressure around the full area of the cylinder head.

Actual operation of the well packer setting tool and cylinder arrangement described in this specification has disclosed that the slips 20 are tripped and set hydraulically at or near the predetermined pressures and values of the shear screws 21.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A well tool, including a tubular body adapted to be positioned in a well casing, said body having a main portion and a head of a larger external diameter than said main portion, said body also having an intermediate shoulder between said head and main body portion having an external diameter which is smaller than said head diameter but greater than the diameter of said main body portion, said shoulder having one or more ports extending therethrough adjacent said head, normally retracted slips on said main

body portion, an expander on said main body portion for effecting movement of said slips into engagement with said casing, an annular cylinder having a skirt slideable along said head and disposed over said shoulder ports, said cylinder having an annular cylinder head slideable along said main body portion and positioned adjacent said slips and shoulder when said slips are in retracted position.

- 10 2. A well tool, including a tubular body adapted to be positioned in a well casing, said body having a main portion and a head of a larger external diameter than said main portion, said body also having an intermediate shoulder between said head and main body portion having an external diameter which is smaller than said head diameter but greater than the diameter of said main body portion, said shoulder having one or more ports extending therethrough adjacent 15 said head, normally retracted means of said main body portion, means on said body for shifting said normally retracted means into engagement with said casing comprising an annular cylinder having a skirt slidable along said head and disposed over said shoulder ports, said cylinder also having an annular cylinder head slidable along said main body portion and positioned adjacent said normally retracted means when said normally retracted means is in retracted position.

20 3. A well tool, including a tubular body adapted to be positioned in a well casing, said body having a main portion and a head of a larger external diameter than said main portion, said body also having an intermediate shoulder between said head and main body portion which is of a smaller external diameter than said head diameter but greater than the diameter of said main body portion, said shoulder having one or more ports extending therethrough adjacent said 25 head, normally retracted means on said main body portion, means on said body for shifting said normally retracted means into engagement with said casing comprising an annular cylinder having a skirt slidable along said head and disposed over said shoulder ports, said cylinder also having an annular cylinder head slidable along said main body portion and positioned adjacent said normally retracted means when said normally retracted means is in retracted position.

30 4. A well tool, including a tubular body adapted to be positioned in a well casing, said body having a main portion and a head of a larger external diameter than said main portion, said body also having an intermediate shoulder between said head and main body portion which is of a smaller external diameter than said head diameter but greater than the diameter of said main body portion, said shoulder having one or more ports extending therethrough adjacent said 35 head, normally retracted means on said main body portion, means on said body for shifting said normally retracted means into engagement with said casing comprising an annular cylinder having a skirt slidable along said head and disposed over said shoulder ports, said cylinder also having an annular cylinder head slidable along said main body portion and positioned adjacent said normally retracted means when said normally retracted means is in retracted position, a tubular setting tool secured to said body and having a head sealed against the inner wall of said body and disposed a substantial distance below said one or more ports, said tubular setting tool having circumferentially spaced slots through its 40 wall extending upwardly from said setting tool head along and a substantial distance on both sides of said ports.

45 5. A well tool, including a tubular body adapted to be positioned in a well casing, said body having a main portion and a head of a larger external diameter than said main portion, said body also having an intermediate shoulder between said head and main body portion which is of a smaller external diameter than said head diameter but greater than the diameter of said main body portion, said shoulder having one or more ports extending therethrough adjacent said head, normally retracted means on said main body portion, means on said body for shifting said normally retracted means into engagement with said casing comprising an annular cylinder having a skirt slidable along said head and disposed over said shoulder ports, said cylinder also having an annular cylinder head slidable along said main body portion and positioned adjacent said normally retracted means when said normally retracted means is in retracted position, a tubular setting tool secured to said body and having a head sealed against the inner wall of said body and disposed a substantial distance below said one or more ports, said tubular setting tool having circumferentially spaced slots through its 50 wall extending upwardly from said setting tool head along and a substantial distance on both sides of said ports.
